UNITED STATES PATENT OFFICE.

JOSHUA S. COSDEN, OF BIGHEART, OKLAHOMA.

OIL DISTILLING AND REFINING APPARATUS.

981,176.

Specification of Letters Patent. Patented Jan. 10, 1911.

Application filed June 2, 1908. Serial No. 436,316.

To all whom it may concern:

Be it known that I, JOSHUA S. COSDEN, a citizen of the United States, residing at Bigheart, in the county of Osage and State 5 of Oklahoma, have invented certain new and useful Improvements in Oil Distilling and Refining Apparatus, of which the following is a specification.

My invention relates to apparatus for refining crude oil or petroleum, wherein heat and steam are employed to separate the crude oil into the fractional distillates, as lubricating oil, cylinder oil, kerosene, gasoline and the like by a process of heating 10 and condensing; all of which will be, hereinafter, fully explained.

The objects of my invention are: to provide a safe and efficient apparatus for separating petroleum or crude oil into its more 15 important fractional distillates; to provide continuous distillation; to provide an apparatus easily repaired and cleaned; and to save time and expense in producing desired 20 results. I attain these objects by the mechanism illustrated in the accompanying drawings, forming a part of this specification, in which:

Figure 1 is a longitudinal vertical section of the furnace or heating room, except the 25 upper portion which is partly broken away to disclose interior parts; Fig. 2 is a detail view, in elevation, of a portion of the heating pipes; Fig. 3 is an elevation of the primary and secondary series of condensers; Fig. 4 30 is a transverse sectional view, on line $\alpha-\alpha$ of Fig. 1, of the heating room.

Similar letters refer to similar parts in the several views.

Referring to the drawings, A designates 40 the furnace or heating room having a smoke stack B; and having within said heating room a series of, nearly, horizontal heating pipes C, arranged in a convenient manner, preferably, in a vertical series near each side 45 wall of the heating room and extending, approximately, to the roof of the said room, all of said pipes being connected by U-shaped end connections C' and supported by the upright frames t. See Figs. 1 and 4. 50 The fuel (gas) pipes v are supported by the arms W secured to the posts W'. See Figs. 1 and 4.

To prevent "scorching", coloring the 55 products and coking in the pipes, and to aid vaporization, water from a supply, not shown, is forced through the water pipe a

into the elevated water tank D, and through its outlet pipe b with its check valve b' into the uppermost one of the series of heating pipes C, and to indicate the water pressure, while the pump is active, the water gage d is secured in the top of the water tank D, which is provided with a drain pipe c having a check valve c' to control the flow of water therethrough, when draining said tank. Near said water tank D is located an oil supply tank E having an inlet pipe e and a drain pipe e'' provided with a check valve e'; and to convey the crude oil from said tank E into the heating pipes C, the oil pipe f is provided, having a check valve f' to control the flow of oil therethrough, from a source, not deemed necessary to show.

To guard further against "scorching" and coloring the contents of the heating pipes C and to prevent them from becoming coked, or clogged by defective heat and by temporary cessation of operation, the steam injecting pipes g, having check valves g' are provided, to be used as required, each of 80 said pipes having one of its ends entering one of the heating pipe connections C' and the other end connecting with a highly heated steam boiler, not shown, but understood. To indicate the pressure in said heating pipes, a steam gage h' is secured to the upper end of the steam pressure pipe h, being connected with the heating pipes C. See Fig. 1. The residuum of sand, clay and asphalt, in the crude oil incapable of being 85 vaporized without excessive heat, passes slowly along through the said heating pipes which have a slight downward inclination, and, to catch and remove the residuum, the pipe i is connected with the under side of 90 one of the U-shaped pipe connections C' and with the residuum tank F, said tank having a drain pipe i'' which has a check valve i'', said tank having a pressure gage i''' to indicate the pressure in that part of the heating system and to indicate when the tank 95 is full or the pipe i is clogged.

To catch the residuum that escaped being caught by the pipe i and tank F, the tank G is provided having an inlet pipe j, an outlet 105 or drain pipe j', with its check valve j'', and a pressure gage j''', and to catch still other insoluble matters, as sand, clay, asphalt and the like, the tank H is provided, having an inlet pipe k, a drain pipe k' with a 110 check valve k'' and having a pressure gage k'''.

See Fig. 1.

The residuum pipes *i*, *j* and *k* have a slight inclination downward to their tanks which may be increased to any desired number, to remove all residuum which being 5 heavier than the vapor moves along the inner surface of said heating pipes, and enters the residuum pipes and tanks which have vapor in them until displaced by the residuum, which has the greater specific gravity, forcing the vapor out of the tanks and 10 back into the heating pipes C.

The main outlet pipe I is in effect a continuation of the heating pipes C and conveys their vapor contents into the condenser A¹, being the first of a primary series of condensers A¹, A², A³, A⁴, A⁵, A⁶, A⁷, A⁸, A⁹, A¹⁰, and A¹¹, each of which is connected with the next adjacent one by the connecting pipes *m*, *m*¹, *m*², *m*³, *m*⁴, *m*⁵, *m*⁶, *m*⁷, *m*⁸, 15 and *m*⁹; said condensers being provided with drain pipes *n*, *n*¹, *n*², *n*³, *n*⁴, *n*⁵, *n*⁶, *n*⁷, *n*⁸, *n*⁹, and *n*¹⁰, 20 said pipes having check valves *o*, *o*¹, *o*², *o*³, *o*⁴, *o*⁵, *o*⁶, *o*⁷, *o*⁸, *o*⁹, and *o*¹⁰. See Fig. 3.

It will be understood that the number of 25 condensers may be increased as desired, the number shown and described being sufficient in the present case.

To obtain the best results in producing the lighter fractional distillates, as kerosene, 30 benzine, gasolene, etc. a secondary series of condensers B¹, B², B³, B⁴, B⁵, B⁶, B⁷, B⁸, B⁹, B¹⁰ and B¹¹ is installed upon a plane above the said primary series of condensers. See Fig. 3.

35 Each condenser in the lower or primary series is connected with a like numbered condenser of the upper or secondary series, A¹ of the lower series being connected with B¹, of the upper series, by the vapor pipe P, 40 condenser A² connected with condenser B² by vapor pipe P', and so on throughout the series. The condensers of the upper or secondary series have drain pipe *q*, *q*¹, *q*², *q*³, *q*⁴, *q*⁵, *q*⁶, *q*⁷, *q*⁸, *q*⁹, and *q*¹⁰, having check valves 45 *r*, *r*¹, *r*², *r*³, *r*⁴, *r*⁵, *r*⁶, *r*⁷, *r*⁸, *r*⁹, and *r*¹⁰, to control their discharge. See Fig. 3.

The vapor pipes P, P¹, P², P³, and P⁴, have their lower ends extended down into each of the primary or lower condensers in 50 the first five A¹, A², A³, A⁴, and A⁵, being shown in A¹, where the condenser is broken away, and indicated in the others by broken lines.

Each of the upper or secondary series of 55 condensers may have a reservoir of its own in which to discharge its contents, when it is desired to make "fine cuts"; but for ordinary purposes their drain pipes may be grouped, as in the present case, two or more 60 of their drain pipes leading the contents of their condensers into one storage tank or reservoir, as M, N, and O, and Q, R, and S, their contents usually, having passed through cooling boxes, as J, K, and L, or 65 any convenient style or form, each having a

drain pipe, J', H', and L', being shown. See Fig. 3.

In operation, to prevent the oil in the heating pipes from "scorching", and coloring the products, or igniting, water is first 70 introduced into the heating pipes C through the water pipe *a*, from a supply, not shown, through the tank D and the pipe *b*; immediately following the water the crude oil or petroleum is forced through the oil pipe 75 *e*, the tank E and the pipe *f* into the heating pipes C to which heat is applied, by means of the fuel pipes *v* and *v'*, transforming the crude oil and water within said pipes into a combination of vapors, of varying specific 80 gravity, which separate upon cooling, forming a variety of fractional distillates, as lubricating oil, cylinder oil, kerosene and gasolene, the heavier products condensing first and at the higher temperature of near 600° 85 (Fah.), in the first condenser A¹, gradually decreasing in temperature to 80° to 100° (Fah.) in the last A¹¹, as the vapor passes through from first to last of the primary or lower series of condensers A¹ to A¹¹ by 90 means of their connecting pipes *m*, *m*¹, *m*², *m*³, *m*⁴, *m*⁵, *m*⁶, *m*⁷, *m*⁸, and *m*⁹, where the temperature is reduced to near 100° (Fah.) in the last said condenser.

From the lower or primary series of condensers the lighter vapor passes up through the vapor pipes and into the upper or secondary series of condensers; B¹, B², B³ etc., the temperature in said condensers being slightly lower than in the corresponding 100 condensers of the lower or primary series, the heavier vapors retaining heat longer.

The drain pipes of all the condensers, are normally closed except the last one *q*¹⁰, it being kept open to afford a draft for the vapor 105 to flow, from one condenser into another, through their pipe connections, as shown in Figs. 1 and 3.

Where fine "cuts" are not necessary the 110 contents of two or more condensers of either series may be combined in one storage tank, as tank S, which contains heavy lubricating oil, the product of condensers A¹, A², A³, and A⁴.

Tank Q contains cylinder oil, being the 115 product of the condensers A⁵, A⁶, A⁷ and A⁸; tank R contains kerosene being the product of condensers A⁹, A¹⁰ and A¹¹; the storage tank M contains a light lubricating oil, being the products of condensers B¹, B², B³ 120 and B⁴; the contents of storage tank N is a light cylinder, floor or wood oil being the product of condensers B⁵, B⁶, B⁷ and B⁸; and the contents of the storage tank O gasolene, being the product of condensers B⁹, 125 B¹⁰ and B¹¹. See Fig. 3.

The quality of the contents of the storage tank S, lubricating oil, can be changed by turning the drain pipe *n*⁴ of condenser A⁶ into it; likewise, the contents of storage 130

tank Q can be changed by turning the drain pipe *n*^s of the condenser A^o into it; the same course may be pursued with regard to the storage tanks M, N and O, as the contents of each condenser differs from the one before and after it. The residuum or insoluble matter requiring more than 600° (Fah.) to vaporize passes slowly along within said heating pipes, (on account of their inclination) and is caught in the residuum pipes *i*, *j* and *k* and conveyed into the residuum tanks F, G and H. See Fig. 1. The residuum being heavier than the vapor the vapor is crowded out of said tanks to the extent that the residuum displaces it.

The gages *i*'''', *j*''' and *k*''' indicate variations of pressure in the heating pipes and any stoppage or clogging of the residuum pipes *i*, *j* and *k*. The said tanks should not be allowed to fill completely before "draining off" otherwise the application of heat might become necessary.

After the refining apparatus is started and in active service oil and water are forced into the heating system simultaneously, and nearly continuously, and the upper portion of the heating system has a temperature maintained at or above 600° (Fah.).

In case the heating pipes become coked or clogged, or the contents fall below the proper temperature from temporary cessation of operation, or from any cause, through the pipes *g* super-heated steam is injected.

The water which is forced into the heating system is converted into steam and mingles with the oil vapors, giving them a good "wash" and improving the color of the products arising therefrom. Said steam settles as water in the bottom of the condensers, and tanks which are sufficiently low in temperature to permit the same, and from said condensers and tanks the water is first drawn off, as waste, then the oil, as the water and oil separate upon condensation.

Having thus described my invention, what I claim as new and useful and desire to secure by Letters Patent is—

1. In an apparatus for refining crude oil and petroleum; a series of nearly horizontal heating pipes C containing the crude oil and water converting the same into vapor arising therefrom; a series of primary condensers the first of the series being connected with said heating pipes, and each condenser of said series having a pipe connecting it with the next adjacent one, except the last, to receive the contents of said heating pipes to condense the same into the commercial products of varying degrees of density and gravity; a secondary series of condensers above the plane of said primary

condensers and receiving their contents from the primary condensers through pipe connections for making a lighter variety of products each condenser being provided with a controlled outlet pipe, substantially as set forth.

2. In an apparatus for refining crude oil or petroleum; a series of nearly horizontal heating pipes containing the crude oil and water converting the same into vapor arising therefrom; a series of primary condensers the first of the series being connected with said heating pipes, and each condenser of said series having a pipe connecting it with the next adjacent one, except the last, to receive the contents of said heating pipes to condense the same into commercial products of varying degrees of density and gravity, a secondary series of condensers above the plane of said primary condensers and receiving their contents from the primary condensers through connecting pipes for making a lighter variety of products each condenser being provided with a controlled outlet pipe; a series of residuum tanks having inlet pipes connected with said heating pipes to receive and remove from said heating pipes the insoluble matter, as described.

3. In an apparatus for refining crude oil and petroleum; a series of nearly horizontal heating pipes containing the crude oil and water converting the same into vapor arising therefrom; a series of primary condensers the first of the series being connected with said heating pipes, and each condenser of the said series having a pipe connecting it with the next adjacent one, except the last, to receive the contents of said heating pipes to condense the same into the commercial products of varying degrees of density and gravity; a secondary series of condensers above the plane of the said primary condensers and receiving their contents from the said primary condensers through connecting pipes for making a lighter variety of products each condenser being provided with a controlled outlet pipe; a series of residuum tanks having inlet pipes connected with said heating pipes to receive and remove the residuum matter; a series of steam injecting pipes *g* connected with the said heating pipes to prevent the contents of said pipes from scorching and clogging, as set forth.

In testimony whereof I affix my signature in presence of two witnesses.

JOSHUA S. COSDEN.
